UNITED STATES PATENT OFFICE.

WILHELM ZÖRNSCH, OF COLOGNE, GERMANY.

ADJUSTABLE DRAWING-BOARD.

No. 881,276.

Specification of Letters Patent.

Patented March 10, 1908.

Application filed July 31, 1906. Serial No. 328,558.

To all whom it may concern:

Be it known that I, WILHELM ZÖRNSCH, a citizen of the German Empire, and resident of Cologne, Germany, have invented certain new and useful Improvements in Adjustable Drawing-Boards, of which the following is a specification.

This invention has for its object an adjustable drawing board of cardboard or the like, for freehand drawing.

The essential feature of the invention consists therein that the support on the back of the board is joined to the board by a band which can be adjusted with regard to length, 15 and which, according to the length, is stretched by a smaller or larger adjusting-flap, in order to be able to adjust the support in the stretched positions which correspond with the length of the band. The fixing of 20 the support in the spread position makes it possible to give to the drawing-board the most different angular positions in the various positions of the same.

The subject of the invention is illustrated 25 on the accompanying drawing, where

Figures 1 to 4 show the same in different positions in a side-view, the small flap being used as a fixing device for the support, while Figs. 5 to 8 show the same views with the 30 large flap as a fixing device. Fig. 9 shows the drawing board in a front view, and Fig. 10 is a back view on a reduced scale.

Similar letters refer to similar parts throughout the several views.

35 On the back of the drawing-board *a*, whose front-side serves to hold the drawing paper is fastened the support *b*, which can be turned up, for which purpose the board *a* carries a rigidly fixed slat *g*, to which is 40 hinged the support *b*. The support *b* itself carries a small adjusting-flap or brace *c* and a large adjusting flap or brace *d*, which are both hinged to the free end of the support at *o*.

45 The free end of the support *b* is connected to the board *a* by means of a band of adjustable length. In the embodiment shown in the drawing the band consists of two separate parts *e*' and *e*². The part *e*' has one of 50 its ends secured to the board *a* in any suitable manner, such as by having the end passing through a slot in the board and glued to the front of the board below the paper covering. The part *e*² has one end se-

cured to the support *b*. The free ends of the 55 parts *e*' and *e*² can be connected together at different points to change the length of the band, and for that purpose the part *e*' carries a pair of head members *s* which are spaced from each other, and the part *e*² is provided 60 with a socket member *t* which is adapted to engage either of the head members to form a head and socket fastener.

With the aid of the two-part band *e*' *e*² the free end of the support *b* can be connected 65 with the board *a* in different positions. In order to secure or fix the parts in this position the band *e*', *e*² is stretched either with the aid of the small adjusting-flap *c* (Figs. 1 to 4) or in the lengthened state by means of 70 the large adjusting flap *d* (Figs. 5 to 8). By this stretching of the band the support is secured in its position with regard to the drawing-board and the board can thus be adjusted on a table *f* under the most different 75 angles to the table, as will be seen at once from the drawing.

What I claim as my invention and desire to secure by United States Letters Patent is—

1. The combination with a drawing board, 80 of a support hinged at one end to the back of the board, a longitudinally adjustable flexible connection between the free end of the support and the board, and braces of different length adapted to secure the board and the support in the different angular positions determined by the length of the flexible connection.

2. The combination with a drawing board, 85 of a support hinged at one end to the back of the board, a band of adjustable length connecting the free end of the support and the board, and a plurality of flaps of different length hinged at one end to the support and 95 having their other ends adapted to rest against the back of the board to secure the support and the board in the different angular positions determined by the length of the band.

In testimony whereof I have signed my name to this specification in the presence of two subscribing witnesses.

WILHELM ZÖRNSCH.
